UNITED STATES PATENT OFFICE.

LEVI W. STOCKWELL, OF CLEVELAND, OHIO.

DRIVE-CHAIN.

SPECIFICATION forming part of Letters Patent No. 223,683, dated January 20, 1880.

Application filed May 17, 1879.

To all whom it may concern:

Be it known that I, LEVI W. STOCKWELL, of Cleveland, in the county of Cuyahoga and State of Ohio, have invented certain new and useful Improvements in Detachable Drive-Chains; and I do hereby declare that the following is a full and exact description thereof, reference being had to the accompanying drawings, making part of this specification.

10 My invention relates more particularly to that kind of drive-chains which are composed of alternate open links and connecting-sections or double-hook couplers.

15 Previous to my invention chains of this kind have been made, some with the links and couplers articulated in such a manner that the parts composing the chain were inseparable; others with the articulated parts detachable under certain conditions, so that while the parts of 20 the chain were not liable to casual separation they could be designedly uncoupled for purposes well known to those skilled in the art. But in all the forms of chains of the kind first above referred to, and having the parts capable of detachment, as just above mentioned, it 25 has been necessary, I believe, to either have the ends of the links cut, or to have either the end bars or the side bars weakened by some sort of depression, notch, or cut-away employed 30 to render the parts capable of detachment; and in all such cases, I believe, it has been necessary that the coupler should be composed of a sort of C-shaped device—that is, a sort of double hook.

35 Now, in all such detachable chains as heretofore constructed both the cutting or reduction in size of any part of the link, to adapt it to be detached from the coupler, and the open hook-form of the coupler device are objectionable features, the first because of the tendency to weaken the link, the second because of the necessity, in such form of coupler, of making the back or body of the coupler very thick and heavy, to get sufficient strength of stock; 40 and in all such chains there is, besides, a liability of accidental detachment of the parts.

To overcome these objections, and at the same time provide for use a detachable drive-chain of efficiency, are the main objects of my 45 invention, which, to these ends, consists in a chain composed of alternate links and duplex

coupler-hooks, the said duplex coupler-hooks being so made and adapted to slide one within the other, as will be presently fully described, that, while they effect the retention together 55 of the parts of the chain, they must be purposely separated to permit a detachment of the parts, all as will be hereinafter more fully described.

To enable those skilled in the art to make 60 and use my invention, I will proceed to fully explain the construction and operation of a chain made in accordance therewith, referring, by letters, to the accompanying drawings, in which—

65 Figure 1 is an elevation or face view of a chain embodying my invention. Fig. 2 is an edge view of the same. Fig. 3 is a partial longitudinal section at the line α α of Fig. 1. Fig. 4 is an edge view of two links and a 70 coupler, illustrating the position of the parts necessary for the separation of the parts composing the duplex coupler-hook. Fig. 5 is a side or face view of the parts seen at Fig. 4, with the coupler-hooks partially separated; 75 and Fig. 6, detail view, showing the parts of the coupler separated.

80 In the several figures the same parts will be found designated by the same letter of reference.

85 A B C are the links of the chain, which are represented as being made, by preference, about rectangular in contour, and with their end and side bars about cylindrical in form. These links are connected together or coupled to form the chain by what I have called a “duplex coupler-hook,” which is composed, as shown, of two C-shaped open or double hook pieces, D E, adapted to slide and fit one within the other, and one or both of which has its 90 side opening large enough to permit the passage through it at the same time of the side bars of two of the links—that is to say, either or both of the hooks D and E must have the side opening or openings large enough to permit the separation of these parts in the manner illustrated at Figs. 4 and 5, the side bars of the two links, placed face to face, having, as illustrated, both to pass through the opening in hook E.

95 100 If it should be deemed expedient to have the separation of the parts D and E effected

with the links in a position just opposite to that shown at Fig. 4, then the side opening of part D should be made larger than shown, and that of E might be made smaller, or could be 5 left the size shown.

It will be understood that as to the operations for uniting and uncoupling the parts of the chain at any point, for any of the known purposes, it is only necessary, in the detachment of the parts, to turn any two adjacent links and the duplex-coupler device connecting said links into the positions shown at Fig. 4; then slide the parts D and E away from or 10 out of association with each other, as indicated at Fig. 6, one of these parts, D, maintaining its relation to the links A, B until the removal of part E, when, either separately or both at once, according to the size of the side opening in part D, the said links and part D 15 of the duplex coupler may be separated.

To unite or recouple two links and their connecting devices, the reverse of the operations just explained is, of course, performed.

In the use of my improved chain, while the 20 articulated parts have the same freedom of action, said parts are not liable to any disunion except by design; for, in order to uncouple them, they must not only be brought into the precise relative position of coupler 25 and two links shown at Fig. 5, but also must then be manipulated in the precise manner described and shown at Fig. 6; and it will be observed that in a chain made as shown and described all the bars of all the links are uniformly 30 35 form in size and strength; and that, by reason of the coupler being made of two C-shaped parts, D and E, the back, or body portion of each closing up the opening of the other, not only are the confined or coupled end bars of 40 the links entirely surrounded or bound round

by the coupler, but these two parts or devices D and E act as re-enforces to each other, so that, in their aggregate condition, they may be made to constitute a coupler equally as strong as a single open or C-shaped device, 45 with less weight of stock and of a more desirable shape.

Of course, in practicing my invention, modifications in the sizes, proportions, and details of structure of the parts may be made without departing from the spirit of the said invention; and I wish to be understood as not limiting the scope of my invention to any such particularities, so long as a chain is made embodying the gist of my invention, which may be said to rest in the idea of a chain in which the union of a series of plain open links is effected by means of duplex couplers, substantially such, in principle of construction and operation, as the coupler I have shown and described.

What I claim as of my invention, and desire to secure by Letters Patent, is—

1. A coupler for drive-chains composed of two C-shaped pieces adapted to engage the 60 links of a chain by sliding one part of the coupler over the other in substantially the manner and for the purposes described.
2. A drive-chain composed of alternate plain open links and duplex coupler devices, 70 one adapted to slide over the other, the said links and duplex couplers being combined and operating together, substantially as set forth.

In witness whereof I have hereunto set my hand and seal.

LEVI W. STOCKWELL. [L. S.]

In presence of—

L. H. PRATT,
W. H. HAWKINS.
